UNITED STATES PATENT OFFICE.

GEORGE L. MANSFIELD, OF CHICAGO, ILLINOIS.

DERAILER.

SPECIFICATION forming part of Letters Patent No. 728,740, dated May 19, 1903.

Application filed August 18, 1902. Serial No. 120,037. (No model)

To all whom it may concern:

Be it known that I, GEORGE L. MANSFIELD, a citizen of the United States, residing at Chicago, in the county of Cook and State of Illinois, have invented certain new and useful Improvements in Derailers, of which the following is a specification.

My invention relates to derailing-switches; and the object of my invention is to provide a simple derailler which may be applied upon either the inside or outside of the rail and which, being placed in position, will insure the derailing of a car or train moving toward and upon it.

Wrecks are frequently caused by the escape of cars from sidings and their movement onto the main track. To avoid this, I apply a device which is thrown over or across the rail after cars have been placed on the siding and which will derail the cars if from accidental causes they start back toward the main-track switch. The devices which have hitherto been designed for this purpose have been more or less objectionable because of their weight and cost, and particularly because of their height above the rail, which cause them to interfere with a passing train, even when thrown out of operating position.

A particular object of this invention is to provide a derailler which may be automatically actuated from the switch or from the watch-tower and which when moved away from the rail will fall below the level of the rail-head, so that it will be entirely below the truck-bases of passing cars.

Another particular object of the invention is to improve the construction of deraillers with regard to the size and weight thereof and to standardize the same for employment with rails of different heights.

My invention consists generally in a derailler provided with a wheel-lifting portion and a deflecting rib or shoulder to force the wheel off the rail and pivoted operating means axially parallel with the rail.

My invention further consists in various constructions and in combinations of parts, all as hereinafter described, and particularly pointed out in the claims.

The invention will be more readily understood by reference to the accompanying draw-

ings, forming a part of this specification, and in which—

Figure 1 is a plan view of a derailler embodying my invention. Fig. 2 is an elevation thereof, the rail and ties being removed. Fig. 3 is a transverse vertical section on the line 3^x of Figs. 1 and 2 viewed in the direction of the arrow and showing the derailler removed from the rail. Fig. 4 is a similar sectional view on the line 4^y of Figs. 1 and 2, showing the device in derailing position; and Fig. 5 is a view like unto Fig. 4, illustrating the positions of the parts during the first part of the throw-out movement of the derailler.

My device may be applied either at inside or outside of the track-rail and may be operated by a hand-lever, though, preferably, it is connected with the switch-stand of the adjacent switch. The derailler proper comprises the plate 2, adapted to rest upon the top of the rail 3 and preferably provided with the overhanging lip or flange 4. The top of the plate is provided with the wheel or tread lifting block 5, integral with the plate and having its end 5' extending beyond the end of the plate 2 and beveled or inclined, as shown at 5". The opposite end of the block 5 tapers down to the plate, and the top of the block, preferably flat, as shown, is parallel with the top of the rail. The plate 2 is formed with the high diagonal deflecting shoulder or rib 6, extending from corner to corner of the plate 2 and adapted to be engaged by the flange of 85 the wheel after the wheel has been lifted by the block 5. It will be noted that the gap or notch 2" at the end of the plate between the block 5 and the outer end of the rib 6 is sufficiently deep to prevent the striking of the 90 wheel-flange upon the end of the plate when the wheel first rolls upon the block 5. In this way the plate is relieved from pressure at a point overlying the flange of the rail and beyond the head of the rail, as the tread of the 95 wheel is carried upon the flat top of the block 5 until the side of the wheel-flange engages the rib 6 and until the wheel has been forced laterally across the plate until it is nearly over the head of the rail, after which there is no bending strain upon the plate. By reason of this construction I am enabled to employ

a much lighter plate than usual, with a consequent saving in cost. Furthermore, the device for supporting the outer edge of the plate may be lighter than usual.

5 The length of the device preferably somewhat exceeds the overlying distance of two ties, to which the device is secured.

77 are plates secured upon the tops of the ties and provided with ears or lugs 8 and 9, 10 these lugs being oppositely arranged upon the two plates. The outer lugs 8 are provided with the horizontal pins 10 for the supporting-links 11, the upper ends of which are pivoted upon ears 12, provided on the outer 15 edge and corners of the plate 2. The pivot-pins are all parallel with the rail, and when the derailer is in position above the rail the links incline toward the head of the rail, so that pressure applied on the top of the device 20 rail tends to hold the device against the side of the rail and against the outward-moving force of the wheel-flange when acting upon the inclined rib or shoulder 6.

The movement of the derailer toward the 25 side of the rail is limited by the lugs 13, which depend from the under side of the plate 2 and which incidentally serve as attachments for the operating device. This operating device comprises the links or arms 14, fixed upon the 30 rock-shaft 15, that is held in and between the lugs 9 on the plate 7. The rock-shaft is operated by the crank-arm 16, that is connected with a suitable operating-lever or with the adjacent switch-stand if automatic operation is 35 wished for. The upper ends of the arms 14 are provided with the inclined slots 17, engaged with the pins 18 in the lugs 13, whereby the plate may be moved back and forth toward the rail-head. Because of the depending lip 40 or flange 4 on the plate which overhangs the rail-head it is necessary to raise and free the end of the plate before it can be started back and thrown away from the rail. This function is performed by the inclined slots and 45 pins 18, it being evident that upon the first movement of the arms 16 and arms 14 the first tendency of the arms 14 will be to wedge the pins upwardly, the weight of the plate and the engagement of the lip 4 with the rail resisting 50 the outward-throwing tendency of the arms 14. As soon as the free end of the plate has in this way been wedged upward far enough to relieve the lip 4 the continued movement of the arms 14 will throw the plate away from 55 the rail, and after the links 11 and arms 14 have passed the vertical position the plate will fall of its own weight. The plate falls backwardly upon the links and arms, as shown in Fig. 3, and the top of the plate drops below the head of the rail, being thus safely removed from the path of depending parts on the cars that may pass over it. When the arm 16 is again operated, it is obvious that the plate will be lifted and swung toward the 60 rail and striking the beveled corner of the rail will slip over the top thereof. The length of the slots 17 in the arm or arms 14 is such

that the plate is permitted only a small vertical movement with relation to the arms 14 when the same are in an approximately vertical position. In order to permit the full backward fall of the plate and links 11, I find it desirable to elevate the centers of the shaft 15 above the centers of the pins 10 or else make the arms 14 longer than the links 11.

When my device is to be used upon small track-rails, the plates 7 are sunk in the ties. It will be noted that the plate 2 has the projecting tapered end 19 and the end notch 20. These are provided to prevent the derailment 80 of a train passing onto the siding before the derailer has been thrown out.

As numerous modifications of my invention will readily suggest themselves to one skilled in the art, I do not confine the same to the specific construction herein shown and described.

Having thus described my invention, I claim as new and desire to secure by Letters Patent—

1. The derailer comprising the plate provided with a deflecting rib or shoulder and adapted to rest upon the top of the rail, in combination with operating means for moving said plate toward and from said rail and for depressing said plate below the level of the rail-head, substantially as described.

2. The derailer comprising the plate provided with the wheel-block and the deflecting rib or shoulder and adapted to rest upon the head of the rail, in combination with operating means for moving said plate in horizontal and vertical planes to engage or disengage the plate from said rail and said means adapted to fold with said plate at the side of the rail, substantially as described.

3. The derailer comprising the derailing-plate proper provided with a rail-engaging lip, in combination with a mechanism operating said plate vertically and horizontally in movement both toward and from the rail, substantially as described.

4. The derailer proper provided with depending rail-head-engaging parts, in combination with operating means for moving said derailer on, to and away from the rail and said operating means first raising said plate to disengage same from the rail before moving the derailer away from the rail, substantially as described.

5. The derailer proper in combination with suitable supports for the free edge thereof and an operating arm or arms operable to first lift said derailer and then move the same away from the rail, substantially as described.

6. The derailer proper in combination with the pivotal supports for the outer edge thereof, a rock-shaft and operating-arms provided thereon and pivotally attached to the under side of said derailer, substantially as described.

7. The derailer proper comprising the plate provided with the wheel-block and the deflecting rib or shoulder, in combination with

- tie-plates, the links pivotally connecting the same and said plate and means for moving said plate horizontally, substantially as described.
5. 8. The derailer comprising the derailer proper, the tie-plates, the folding links pivotally connecting said tie-plate and derailer proper and the operating-arms connected with said plate for folding the same backwardly and downwardly or raising the same, substantially as described.
9. The derailer comprising the plate 2 provided with the overhanging lip 4, the wheel-block 5 and the deflecting shoulder or rib 6, in combination with a support for the outer edge of said plate, the operating-arms and means interposed between said operating-arms and said plate automatically operating to lift the plate before the outward movement thereof, substantially as described.
10. The derailer comprising the derailer proper in combination with the parallel links or arms pivotally supporting and attached thereto for maintaining said derailer substantially horizontal in all positions and means for operating said links, substantially as described.
11. The derailer comprising the derailer proper in combination with the parallel links or arms pivotally supporting and attached thereto for maintaining said derailer substantially horizontal in all positions, the wedging devices interposed between the arms that are positively actuated and said derailer, and means for operating said arms, substantially as described.
12. The combination with the rail and ties of the derailer comprising the plate having wheel lifting and deflecting portions, the tie-plates, the supporting-links pivotally connecting the same with the derailer-plate and the plate-operating mechanism, the axes of said links and said mechanism being parallel with and distant from said rail, substantially as described.
13. The derailer comprising the plate 2 provided with wheel - deflecting portions and adapted to rest upon a rail-head, in combination with a normally inclined pivotal support for the outer edge of said plate, the pivotal operating-arms provided with inclined slots 17 in their upper ends and the pins upon the said plate engaging said slots and means for operating said arms, substantially as described.
14. The derailer comprising the plate provided with a deflecting portion and a rail-head-engaging lip or flange, said plate being adapted to rest upon the top of the rail, in combination with operating means for actuating said plate to successively disengage its lip or flange from the side of the rail and swing said plate away from the side of and below the top of said rail, substantially as described.
65. 15. The derailer comprising the plate provided with car-wheel raising and deflecting portions and a depending lip or flange, in combination with operating means for automatically lifting and disengaging said lip when the derailer is moved away from the rail and means for swinging said plate to and away from the rail in a substantially horizontal position, substantially as described.
16. The derailer comprising the derailer proper, in combination with the arms or links supporting said plate and occupying inclined position when said plate is in operative position and adapted to hold said plate in contact with the side of said rail when top pressure is exerted upon said plate, and the operating means for swinging said plate, substantially as described.
17. The derailer comprising a pair of tie-plates provided with journal and pivot lugs or bearings, in combination with the arms pivotally journaled or secured to said lugs, the wheel raising and deflecting plate pivotally secured to the upper ends of said arms, said arms being arranged to support said plate on two parallel lines of support, means for rocking said arms in a substantially horizontal plane to move said plate in and out of operating position and means for automatically engaging and holding said plate against lateral movement in either direction while a car-wheel passes over same, substantially as described.
18. The derailer comprising a pair of tie-plates provided with pivot-lugs in combination with the arms pivoted on said lugs, the wheel raising and deflecting plate pivoted to the upper ends of said arms, said arms being arranged to support and swing said plate in its horizontal position and fold thereon, said arms being pivoted to the lugs and to the plate so as to occupy an inclined or bracing position when the plate is on the rail, for the purpose of preventing lateral movement of the plate while supporting and deflecting a car-wheel, substantially as described.
19. The derailer comprising the base or bases adapted for attachment to the railway tie or ties and provided with pivot-lugs, the arms pivotally secured to said lugs and rigidly secured to a rocking shaft, the wheel raising and deflecting plate also pivoted to said arms, said arms being arranged to support and swing said plate, to fold thereon, to maintain it in a horizontal position during the movement thereof and to brace it against lateral movement while in its operative position, and suitable operating means, substantially as described.
20. The derailer comprising a suitable base provided with pivot-lugs and journal-bearings and adapted to be rigidly secured to the railway tie or ties, the rocking arms pivotally secured to said lugs and bearings and operatively secured to a rocking shaft provided with an operating-lever, the wheel raising and deflecting plate also pivoted to said arms, said arms being pivoted to said plate to give

lateral movement thereto, to fold thereon when in its inoperative position, to prevent a tilting movement thereof and to resist lateral movement thereof when in its operative position, together with suitable operating means, substantially as described.

21. The derailler comprising the plate with the wheel-block at one end and the wheel-lifting projection 19 and notch 20 at the other end and with the diagonal deflecting-rib, in

combination with means for operating said plate, substantially as described.

In testimony whereof I have hereunto set my hand, in the presence of two witnesses, this 26th day of July, 1902.

GEORGE L. MANSFIELD.
